STRAIGHTENING MACHINE

William E. Kane, Syracuse, N. Y., assignor to
 Kane & Roach, Inc., Syracuse, N. Y., a corporation of New York

Application April 29, 1937, Serial No. 139,760

22 Claims. (Cl. 153—54)

This invention relates to improvements in a straightening machine adapted more particularly for removing undulations from metal sheets or strips, metal bars, rods or the like.

5 The main objects of this invention are to produce a straightening machine of the above mentioned type which may be quickly and easily adjusted to accommodate the same to work of various sizes, shapes and classes and which is sturdy, 10 economical and simple in construction and operation.

In carrying out the above mentioned objects, I have produced a mechanism comprising two units—a vertical unit and a horizontal unit, each 15 unit including a plurality of roll shaft assemblies arranged in two parallel series, and the mechanism embodies the following major features therein:

• 1. Forming the straightening rolls of each unit 20 with a plurality of work receiving passes or grooves arranged in spaced relation to each other axially of the roll, the passes or grooves of each roll being made to vary from each other in size or shape, or both in size and shape, to render the 25 rolls capable of being utilized for straightening articles or members that differ one from another in size and/or shape corresponding to the passes or grooves of the straightening rolls.

2. Adjustably mounting both of the straightening units whereby they may be moved relative 30 to each other in directions extending substantially normal with respect to each other to selectively bring the passes or grooves of the rolls of one unit into cooperative relation with the corresponding passes or grooves of the rolls of the other unit without the necessity of changing or rearranging the rolls in their respective roll shaft assemblies.

3. Providing novel means for adjusting the 40 rolls of each unit relative to each other whereby pieces of work of maximum and minimum sizes and shapes within the scope of the machine may be straightened without the addition of straightening rolls to or the substitution of other rolls 45 for those already in the machine or the rearrangement of the rolls on their respective shafts.

4. Operating the rolls of both units in unison from a common source of power.

5. Providing for the maximum efficiency in 50 operation of the rolls by positively driving all of the rolls from the single source of power.

6. Providing for the maximum life and ease of operation of the machine by protecting the bearings and the various driving gears directly 55 associated with the straightening rolls from the

scale constantly thrown off by the work during the straightening operation and from other foreign abrasive or injurious material by encasing such bearings and gears in suitable housings.

7. Providing novel and efficient means for supporting the straightening rolls in the machine whereby the rolls of one series of each unit may be brought into relatively close axial relation with each other and with the rolls of the other series so that pieces of work which have a much greater 10 variation in their transverse dimensions or diameters may be more expeditiously straightened than has heretofore been practicable.

8. Maintaining each straightening roll against lateral vibrations or being moved in directions 15 normal to the axis thereof away from the cooperating rolls of the other series during the straightening operation by providing bearing supports for each straightening roll shaft at both ends of the straightening roll carried thereby.

9. Providing for correction of the stresses produced upon the work in the second straightening unit tending to twist or distort the work laterally by offsetting the straightening action produced on the work in the straightening unit first entered thereby, by providing means for producing axial adjustment of one of the intermediate straightening roll assemblies in the second straightening unit.

10. Contributing to the efficiency and economy 30 of the construction and operation of the machine by constructing and operating the mechanism of the two units substantially alike and by making the various parts thereof, where possible, interchangeable.

Other objects and advantages pertaining to the construction and to the form, relation and operation of the parts thereof will more fully appear from the following description taken in connection with the accompanying drawings, in 40 which:

Figure 1 is a top plan of a straightening machine embodying the various features of this invention.

Figure 2 is a detail vertical sectional view taken 45 substantially on line 2—2, Figure 1, illustrating the drive connection between the source of power and the two straightening units, the upper and intermediate portions of the second straightening unit being broken away.

Figure 3 is a front elevation of the machine, illustrated in Figure 1, with a portion of the adjusting shaft for the first or vertical straightening unit broken away.

Figure 4 is an enlarged detail horizontal sec- 55

tional view taken on line 4—4, Figure 3, with the intermediate portion of the base and shaft broken away.

Figure 5 is an enlarged vertical sectional view taken on line 5—5, Figure 3.

Figure 6 is a transverse vertical sectional view through the frame of the vertical straightening unit taken substantially in the plane of line 6—6, Figure 1, showing the greater portion of the adjacent roll shaft assemblies in elevation and the rear portion of the base broken away.

Figure 7 is a detail vertical sectional view taken on line 7—7, Figure 1.

Figure 8 is a detail vertical sectional view taken on line 8—8, Figure 3.

Figure 9 is an enlarged vertical transverse sectional view taken through the horizontal straightening unit substantially in the plane of the line 9—9, Figure 3.

Figures 10, 11, 12, 13 and 14 are detail horizontal sectional views taken, respectively, on lines 10—10, 11—11, 12—12, 13—13 and 14—14, Figure 9.

Figure 15 is an enlarged detail transverse sectional view taken substantially on line 15—15, Figure 3, illustrating the manner of producing axial movement of one of the roll shaft assemblies relative to the remaining roll shaft assemblies to the operating means therefor.

Figure 16 is a detail vertical sectional view taken on line 16—16, Figure 10, illustrating the manner of locking one of the roll shaft assemblies to the operating means thereof.

Figure 17 is a detail vertical sectional view taken substantially on line 17—17, Figure 1, showing the manner of producing vertical movement of the horizontal straightening unit, the intermediate and upper portions of said unit being broken away.

Figure 18 is a detail transverse vertical sectional view taken on line 18—18, Figure 14, illustrating the manner of producing movement of the roll shaft assemblies of one series in a direction normal to the axes thereof relative to the roll shaft assemblies of the other series of the same unit.

Figure 19 is a detail vertical sectional view taken on line 19—19, Figure 18.

Figures 20 and 21 are detail sectional views illustrating more or less diagrammatically the manner in which the straightening rolls of the horizontal and vertical straightening units cooperate with each other for straightening pieces of work of various sizes and/or shapes as determined by the contour of the passes or grooves in the several rolls.

As hereinbefore indicated, the straightening machine of this invention comprises two units—a vertical unit V and a horizontal unit H. These units are constructed and operated substantially alike. The difference between the structures of the two units resides primarily in that the roll shaft assemblies of the vertical unit are arranged with the axes thereof extended in vertical planes, while the roll shaft assemblies of the horizontal unit are arranged with the axes thereof extended in horizontal planes. Furthermore, the vertical unit V is mounted to be moved in a horizontal plane relative to the horizontal unit H to bring the straightening rolls thereof into cooperative alignment with the straightening rolls of the horizontal unit, while the horizontal unit H is movable in a vertical plane to bring the straightening rolls thereof into cooperative alignment

with the straightening rolls of the vertical unit, as will hereinafter more clearly appear.

Considering the construction shown in the drawings more specifically, it will be noted by referring to Figures 1, 2 and 3 that the apparatus comprises a base 1 which is common to both the vertical and horizontal straightening units. The vertical unit V is mounted upon the base 1 in somewhat advanced relation to the horizontal unit H, whereby the straightening rolls thereof will be normally maintained in substantially cooperative alignment with the straightening rolls of the horizontal unit H. The vertical unit V is provided with a substantially rectangular frame 2 which is slidably mounted upon the base 1 to permit the unit to have a limited horizontal movement relative to said base, while the horizontal unit H is provided with a similar substantially rectangular frame 3 which is slidably connected with the base 1 to permit the unit H to have a limited vertical movement relative to the base.

The rectangular frame 2 for the unit V comprises a front plate 5 and a rear plate 6, each of which is arranged edgewise in a vertical plane. These plates 5 and 6 are maintained in spaced relation to each other by vertically disposed end members 7 and 8, one of which, as 7, is interposed between the outer ends of the plates 5 and 6, while the other member 8 is interposed between the inner ends of said plates. The front and rear plates 5 and 6 and end members 7 and 8 are secured to each other by any suitable means, as bolts 9, which extend through aligned holes provided in the front plate 5 and members 7 and 8, as indicated in Figures 1 and 3. The front plate 5 is a relatively narrow member, as shown in Figures 3 and 6. The side members 7 and 8 extend from the upper edge of plate 5 downwardly to some distance below the plate and have the lower ends thereof mounted in sliding engagement with corresponding planed surfaces or guide ways 10 formed on the bed 1. The inner sides of the members 7 and 8 are each provided with inwardly extending flanges 7' and 8', respectively, adjacent the lower ends thereof which contact with a corresponding upwardly extending rib 11 connected with the base 1 for limiting the inward movement of the side members. A gib 11 is secured to the upper face of each rib 11' to extend over the corresponding flange 7' or 8' for maintaining the frame 2 against vertical displacement. The rear plate 6 is a relatively wide member and extends from the plane of the upper surfaces of the front plate 5 and end members 7 and 8 to within a relatively short distance of the lower ends of the side members 7 and 8 and of the base 1.

The rectangular frame 3 for the horizontal straightener unit H comprises a top plate 13, a bottom plate 14 disposed in horizontal spaced relation with each other and two vertically disposed end members 15 and 16 arranged between the outer end portions and inner end portions, respectively, of the top and bottom plates 13 and 14. The top and bottom plates 13 and 14 and the end members 15 and 16 of the frame 3 are secured to each other by bolts 9, in the manner illustrated and described, for the frame 2. The top plate 13 is a relatively narrow member, as shown in Figure 1, and is constructed similar to the front plate 5 of the frame 2. The bottom plate 14 of frame 3, like the plate 6 of frame 2, is a relatively wide member which extends rearwardly some distance from the vertical plane of rear edge of top

plate 13. The bottom plate 14 also has a portion of its ends extending outwardly beyond the adjacent end members 15 and 16 into sliding contact with vertically disposed guide ways 17 and 18 formed respectively in the adjacent faces of vertically disposed standards 19 and 20 secured to or made integral with the base 1. Gibs 22 are secured to each of the standards 19 and 20 to prevent lateral displacement of the bottom plate 14 with respect to the guide ways 17 and 18. Furthermore, each of the ends of plate 14 has a projection 23 (see Figure 17) which extends through a respective elongated slot 24 provided in the adjacent or inner vertical surface of the standards 19 and 20 into the interior of the standards, standards 19 and 20 being chambered, as shown in Figures 2, 4 and 17, to receive said projection 23 and the operating means associated with the projections for producing vertical movement of the frame 3 and the mechanism carried thereby.

This operating mechanism, as shown more clearly in Figure 17, includes two nuts 25 each mounted in a respective projection 23 to be maintained thereby against rotation. Associated with each nut 25 is a screw 27 which extends vertically in the corresponding standard and has the upper end thereof journaled in a bearing member 28 secured in the upper end of the standard. The lower end of each screw 27 extends below the corresponding projection 23 and is journaled in a transversely disposed wall or boss 29 formed in the standard at the lower end of the slot 24. Secured to the lower end of each screw 27 is a worm gear 30 which is in meshing engagement with a corresponding worm 31 secured to a shaft 32 which extends in a horizontal plane between standards 19 and 20. The shaft 32 may, as shown in Figure 3, be composed of sections connected by unions 33 to permit the ready adaptation thereof to machines of various sizes. The ends of the shaft 32 are journaled in the standards 19 and 20 respectively, as shown at 34 and 34', Figure 4. Shaft 32 is manually operated by a crank 35 or the like mounted on a stub shaft 36 journaled in the standard 19 and which is operably connected with the shaft 32 by a pinion 37 secured to shaft 36 and a spur gear 38 secured to shaft 32. The screws 27 may each be provided with an annular flange 27' positioned above the bearing member 29 and a thrust bearing 40, may, as shown, be interposed between said flange and bearing member to sustain the screw and frame 3 against downward axial movement, (see Figure 17).

The vertical unit V is adjusted horizontally upon the base 1 in a manner similar to that explained above for producing vertical adjustment of unit H, as shown in Figures 3 and 8. In the apparatus for adjusting unit V, a sectional worm supporting shaft 32' is journaled to rotate about a horizontal axis, in bearing member 42 secured to the side members 7 and 8 near the lower ends thereof. To one end of shaft 32' is secured a sprocket wheel 43 which is connected by a chain belt 44 to a sprocket wheel 45 carried by a stub shaft 36' journaled in a bearing bracket 46 secured to the front plate 5, shaft 36' being adapted to be manually rotated by crank 35. The shaft 32' carries two worms 31', each of which meshes with a respective worm gear 30' secured to the outer end of a respective one of a pair of screws 48. These screws 48 are constructed alike and each extends into a respective end member 7 or 8, as shown in Figure 8. The end members 7 or 8, as shown in Figure 8 and also end members 15 and

16 of frame 3 are chambered to provide maximum lightness consistent with the strength required of them. Each screw 48 is in screw threaded engagement with a respective nut 49 carried by a holding block 50 secured to the base 1, as shown in Figure 8. Each nut 49 is so mounted in its block 50 that it will be maintained thereby against rotation as the screw 48 is rotated in either direction so that said screw will be moved axially relative to the block 50 and base 1 in a corresponding direction. In order to transmit this axial movement of the screws 48 to the frame 2 each screw is provided with an annular flange 52 positioned in a recess in the outer face of the corresponding end member 7 or 8 and a retaining plate 53 is mounted on each screw 48 and secured to the respective end member 7 or 8 for rotatably securing the screw to the member.

Upon the base 1, at the rear of the vertical unit V, is mounted a motor 55 which has the drive shaft 56 thereof operatively connected, in any suitable manner, with a speed reduction gear unit 57 also mounted upon the base 1 intermediate the motor 55 and the horizontal straightening unit H. This gear unit 57 may be of any suitable or well known construction and, therefore, it is believed to not be necessary to illustrate or describe the same in detail, except that the drive shaft, as 58, thereof is arranged in a plane above the motor 55 and extends outwardly from opposite sides of the adjacent portion of the case of said unit, as illustrated in Figures 1 and 2. One end of the drive shaft 58 is operatively connected by a pair of universal joints 59 and a sectional shaft 60 with a drive pinion 61 rotatably mounted in a gear case 62 secured to the outer or inlet end of the frame 2 of the vertical straightener unit V. The other end of the drive shaft 58 is operatively connected by a pair of universal joints 59 and a sectional shaft 63 with a drive pinion 64 rotatably mounted in a gear case 65 secured to the outer or discharge end of the frame 3 of the horizontal unit H. The sections of each of shafts 60 and 63 are arranged in telescopic relation with each other to permit relative axial movement thereof as the straightening units V and H are moved relative to each other and to the gear reducer unit 57 and motor 55. The shaft 63 extends through a relatively large opening 67 in the standard 20 beneath the path of movement of frame 3, as shown in Figure 2.

It will now be observed that, in order to maintain the frame 3 in the upright position, the bottom plate 14 is provided with an upwardly extending projection 14', which has sliding engagement with the adjacent guide way 18, while the end member 16 is provided with a vertically disposed rib 16' which has sliding engagement with the forwardly positioned guide way 18. Furthermore, gear case 65 is provided with vertically disposed bearing surfaces 65' which slidably engage guide ways 17, as shown in Figure 1.

As shown more clearly in Figures 1, 3, 9 and 11 each straightening unit V and H is provided with two horizontally disposed drive shafts 63 and 70. One pair of shafts 69 and 70 extends from within the gear case 62 longitudinally of the frame 2 toward the inner end thereof and the other pair of shafts 66 and 70 extends from within the gear case 65 longitudinally of the frame 3 toward the inner end of the latter frame. As shown in Figure 7, the drive shafts 69 and 70 connected with the vertical unit V are rotated in unison by the hereinbefore mentioned drive shaft 60 through the medium of a train of gears 71. The train of

- gears 71 consists of drive pinion 61, two similar spur gears 72 and 73, each of which is connected respectively with shafts 69 and 70, and two idle gears 74 and 75 rotatably mounted in the case 62, one of the idle gears as 74 being disposed between the drive pinion 61 and gear 72 and the other idle gear 75 being disposed between gears 72 and 73 for transmitting motion therebetween.
- The drive shafts 69 and 70 associated with horizontal straightening unit H are rotated in unison by drive shaft 63 through the medium of a train of gears 77 mounted in gear case 65, as shown in Figure 5. The train of gears 77 consists of drive pinion 64, two similar spur gears 78 and 79 connected respectively to the drive shafts 69 and 70 and an idle gear 80 rotatably mounted in gear case 65. As shown in Figure 5, the gear case 65 in this instance is composed of two sections 65' and 65'', arranged one at either side of the bottom plate 14 and are secured to said plate in any suitable manner as by bolts 81. Inasmuch as gears 78 and 79 are mounted above plate 14 in the upper case section 65' and the drive pinion 64 is positioned below the plate 14 in the lower case section 65'' the idle gear 80 is shown operating in a slot 82 formed in the plate 14, see Figures 2 and 5. The shafts 69 and 70 for both straightening units are each maintained against axial movement in one direction by the coaction of the respective case member 62 or 65 with the particular gear 72, 73, 78 or 79 connected therewith and with a collar 84 or the like secured to each shaft adjacent the exterior surface of the corresponding case member.
- The shaft 69 for each straightening unit V and H extends from the respective gear case 62 or 65 through a plurality of gear cases 86, there being a gear casing 86 for each roll shaft assembly 88 of a series arranged at one side of the path of movement of the work through the machine. The shaft 78 for each straightening unit V and H extends from the respective gear case 62 or 65 through a plurality of gear housings 87, there being a gear housing 87 for each roll shaft assembly 89 of the series of said assemblies arranged at the opposite side of said path of movement of the work. The housings 87 are connected directly to the respective gear shaft assemblies 88, as shown in Figures 9 and 11, while the housings 86 are mounted upon frame 2 or 3 of the respective straightening units V or H in spaced relation to the corresponding series of roll shaft assemblies 89. Shafts 69 are mounted in bearing 90 mounted in one side of each housing 86 for both rotary and axial movement. A suitable stuffing box 91 may, as shown in Figure 11, be connected with each casing 86 opposite the bearing 90 to prevent scale, usually thrown off by the work during the straightening operation or any other foreign material from entering the casing 86 and to prevent the escape of lubricant from the interior of the casing. It is to be understood that shafts 70 are passed through and are journaled in the casings 87 in a manner similar to that described above for shafts 69 and casings 86 and in as much as the structures of the bearings and stuffing boxes for shafts 70 are substantially the same as those for shafts 69, it is thought to be unnecessary to further illustrate or describe them.
- As hereinbefore mentioned each straightening unit V and H comprises the two series of roll shaft assemblies 88 and 89 which are arranged in different planes at opposite sides of the path of movement of the work through the machine. The roll shaft assemblies 88 and 89 in the vertical

unit V are arranged so that the straightening rolls thereof rotate about vertical axes while the roll shaft assemblies 88 and 89 in the horizontal unit H are so arranged that the straightening rolls thereof rotate about horizontal axes.

The construction of the roll shaft assemblies of the two series for the straightening units V and H are substantially alike so that a description of one unit of each series will suffice for a description of them all. For this purpose I have chosen one of the roll shaft assemblies of each series contained in the horizontal unit H and as illustrated more clearly in Figures 9, 10, 12, 16 and 18 the construction thereof is as follows:

Each roll shaft assembly 88 of unit H comprises a substantially rectangular supporting housing 95 which is mounted on the bottom plate 14 of frame 3 for movement relative thereto longitudinally of the frame. This housing 95 is adjustably secured to the plate 14 by bolts 96 which are mounted in T-slots 97 formed in the plate 14 to extend longitudinally of the frame 3 in parallel relation with each other. A guide key 98 is mounted in the upper face of the bottom plate 14 intermediate T-slots 97 for guiding the housing 95 during the movement thereof relative to the bottom plate 14. The gear casing 86 is a sectional member and is shown in Figure 11 as having one section as 86' thereof made integral with the housing 95. A roll supporting shaft 100 extends from within the gear casing 86 through the supporting housing 95 and is journaled in suitable bearings 101 and 102 mounted in the housing 95 with the axis thereof extending in a horizontal plane substantially normal to the axis of drive shaft 69.

Shaft 100 extends some distance beyond the supporting housing 95 and has the outer end thereof rotatably supported in a bearing member 103. Bearing member 103 is mounted on the bottom plate 14 for movement longitudinally thereof in parallel relation with the movement of housing 95 and is releasably secured to the plate by a pair of bolts 104. Bolts 104 are slidably mounted in a T-slot 105 which extends longitudinally of the bottom plate 14 in parallel relation with the slots 97. Mounted upon the shaft 100 intermediate bearing member 103 and the supporting housing 95 is a straightening roll 107 which is clamped to the shaft 100 by a nut 108 screw-threaded on the outer end portion of the shaft adjacent the bearing member 103 and a thrust bearing or collar 109 connected to the shaft adjacent the outer or forward end of housing 95. The straightening roll 107 may be adjusted axially of shaft 100 when necessary to bring the work receiving passes or grooves 107' and 107'' thereof into cooperative alignment with corresponding grooves or passes of the remaining straightening rolls of the same straightening unit. This may be easily accomplished by the insertion of one or more shims or washers (not shown) between the inner end of the roll and the collar 109. In order to cause the straightening roll to rotate in unison with shaft 100 the roll and shaft may be keyed together as indicated at 113, Figure 9.

Shaft 100 is operatively connected with the drive shaft 69 by a pair of bevel gears 114 and 115. Bevel gear 114 is fixedly secured to shaft 100 by any suitable means while gear 115 is connected to shaft 69 by a key 116 to be rotated by said shaft and at the same time is free to slide longitudinally of the shaft to permit adjustment of the roll shaft assembly 88 along the bottom plate 75

14 relative to the drive shaft 69. The gear 115 in this instance, as will be seen by referring to Figure 11, carries the inner ball race of bearing 90 to which it is clamped by a retaining ring 5 plate 118. The bearing 90 is clamped to the gear housing 86 by a second retaining ring or plate 119 which surrounds plate 118. Suitable packing 120 may be interposed between plates 118 and 119 to prevent foreign abrasive material 10 from entering bearing 90 while a similar packing 120 may be disposed between plate 118 and shaft 69 for preventing such foreign material entering the housing 86 and the escape of lubricant from within the housing.

15 Roll shaft assembly 89 is shown in Figure 9 as being carried above the roll shaft assembly 89 by the top plate 13 of frame 3. Each roll shaft assembly 89 comprises a supporting housing 124 which is releasably secured to the top plate 13 by bolts 125 mounted in a pair of T-slots which extend longitudinally through top plate 13 in parallel spaced relation with each other. A guide key 127 mounted in the top plate 13 intermediate T-slots 126 cooperates with bolts 125 for maintaining the housing 124 in predetermined relation with the top plate 13. The housing 124 comprises a relatively shallow upper chambered portion 128 and two pendant side members 129 which extend from the portion 128 in spaced substantially parallel relation with each other longitudinally of frame 3 to within a relatively short distance from the plane of the upper or inner surfaces of the supporting housing 95. The lower ends of side members 129 are secured together 30 by a pair of tie plates 130 secured to the member by screws 131, see Figures 13 and 16. The tie plates 130 extend between the side members 129 in parallel spaced relation with each other and are preferably composed of steel or the like to slidably engage a guide bar 132 and a positioning bar 133 respectively for maintaining the lower portion of the supporting housing 124 against lateral vibratory movement during the straightening operation.

45 The guide 132 and positioning bar 133 are mounted side by side longitudinally of the frame 3 between a pair of supporting or spacing bars 134 which extend longitudinally of the frame 3 in sliding contact with the adjacent inner ends 50 of the housing members 95 and 124 for maintaining said housing members in predetermined spaced relation when the fastening bolts therefor are loosened. As above stated, housing members 128 are spaced but a short distance from the 55 plane of housing members 95. This is so that the straightening rolls carried thereby may be relatively small in diameter and the rolls of each series can be brought into relatively close relation longitudinally of the frame 3 to each other. 60 These rolls can, therefore, be used more efficiently to straighten thin wire or other stock than where relatively large diameter straightening rolls must be used, as in other similar machines, due to the housings of the upper or outer series thereof being supported by a relatively thick, heavy member extending intermediate the two 65 series of housings and which is secured to or made integral with the lower or inner series of housings, and wherein the axes of these large 70 rolls of each series are necessarily spaced a correspondingly greater distance from each other. This use of relatively small straightening rolls not only enables the machine to be used for straightening a large variety of stock which vary 75 greatly in size from each other, but also pro-

vides for economy in construction and operation of the machine. The supporting bars 134, which are relatively thin, flat members, are secured at their ends to the side members 15 and 16 of frame 3 by screws 135 engaging in inwardly projecting lugs 136 provided on said side members, as shown in Figures 1, 3 and 13.

75 The positioning bar 133 has the ends thereof slidably mounted in grooves or channels 138 provided in the end members 15 and 16 and is 10 adapted to be manually moved longitudinally in a manner hereinafter described for adjusting the roll shaft assemblies 89 relative to each other. The positioning bar 133, as shown in Figure 16, extends above the spacing bars to slidably contact the adjacent tie bar 130. The guide bar 132 is loosely mounted between the end members 15 and 16 and between the positioning bar 133 and one of the supporting bars 134, and extends above the supporting bars into sliding engagement with 20 the other tie bar 130. The guide bar 132 also extends below the plane of the supporting bars 134 into grooves 140 provided in the upper or inner side of each housing 95 transversely thereof for operatively connecting the housings 95 and 25 124 to each other at their inner adjacent ends so that said housings are free to move relative to each other in directions longitudinally of the guide bar 132, but are maintained against movement relative to each other in directions extending 30 transversely of the guide bar.

35 Mounted in the housing 124 is a bearing box 142 which is substantially rectangular in cross-section and is guided for movement relative to the housing 124 toward and from the housings 95 35 by guide flanges or members 143 which extend longitudinally along the inner side of each side member 129 adjacent the front and rear edges thereof, as shown in Figure 12. The bearing box 142 projects at its ends beyond the side members 129 and is maintained against axial movement relative to the housing 124 by laterally extending thrust flanges 144 formed at the front and rear ends of the bearing box and which contact with the adjacent vertical edges of side members 129. A roll-supporting shaft 146 extends 40 through the bearing box 142 and is rotatably supported therein with the axis thereof in parallel relation with the axes of shafts 100 of the same unit by suitable bearings 101 and 102 50 mounted at a respective end of said bearing box. Shaft 146 like shaft 100 extends forwardly some distance from the supporting housing therefor for supporting a straightening roll 147 thereon, and has its forward end journaled in a bearing member 148 constructed similar to bearing member 103 for shaft 100. Bearing member 148 is secured by screw 149 to the outer end of an arm 150 which is secured by screws 151 or their equivalent to the upper side of the bearing box 60 142 and extends forwardly therefrom over the forward portion of shaft 146 in spaced relation to said shaft, as shown in Figures 9 and 12. A thrust bracket 154 is secured to the outer end portion of the arm 150. This bracket 154 extends outwardly from said arm away from shaft 146 and into sliding contact with a smooth bearing surface 156 provided on the front vertical edge of the top plate 13 to maintain the arm 150 from being deflected outwardly during the 70 straightening operation by pressure exerted on the outer end of the arm through bearing member 148. The lengths of the bearing surface 156 and of the surface 154 on bracket 154, coacting with surface 156, are such that the required 75

adjustment of housing 124 longitudinally of frame 3 and the adjustment of bearing box 142 relative to housing 124 for adapting the machine to work of different sizes and shapes may be made 5 without re-arranging the bracket 154 on arm 150.

The adjustment of the bearing block 142 relative to the housing 124 is manually accomplished by means of a shaft 160 rotatably mounted, as shown in Figure 10, in the upper portion 128 of housing 124. Secured to shaft 160 are two worms 161 each of which is in meshing engagement with a respective set of worm gear teeth 162 provided on a respective one of two nuts 163 rotatably mounted in the housing portion 128. 10 The nuts 163 are in screw-threaded engagement with a respective one of a pair of screw members 164 which extend downwardly or inwardly from the housing portion 128 intermediate side members 129 and into the arm 150, as shown in Figure 9. The end of each screw-threaded member 164 engaged in arm 150 is provided with a substantially square head 164' which is positioned in a similar recess 150' provided in the inner side of the arm for maintaining 15 the screw member against rotation relative to the housing 124. It will be understood that there is one of these adjusting units for each roll shaft assembly 89 so that by rotating a shaft 160, the roll shaft 146 and the straightening 20 roll mounted thereon may be moved relative to the housing 124 toward and from the path of movement of the work through the straightening unit in which said roll is mounted. Each shaft 160 has the forward end thereof extended a short distance outwardly beyond the 25 housing portion 128 and provided with a square portion 160' by which said shaft may be operatively engaged by a wrench, crank or the like (not shown) whereby the shaft may be manually 30 manipulated.

The means for adjusting each roll shaft assembly 89 longitudinally of the frame 3 comprises the hereinbefore mentioned positioning bar 133, which, as shown in Figure 13, extends longitudinally through the frame 3 and is common 45 to all the roll shaft assemblies 89 in the straightening unit H. Each of the roll shaft assemblies 89 is provided with a control means for releasably securing the same to the positioning bar so that each roll shaft assembly 89 may be moved 50 independently of the remaining roll shaft assemblies 89 of the same unit when the positioning bar 133 is operated.

The positioning bar 133 is adapted to be manually moved longitudinally with respect to the frame 3 in either direction, and for this purpose the end of the bar 133 at the outer end of the frame 3 is extended a short distance beyond the frame and provided with a rack 166. A pinion 167 meshing with the rack 166 is secured to a short shaft 168 which is journaled in a bracket 169 secured to the end member 15, as shown in Figure 13. One end of shaft 168 is extended outwardly beyond the adjacent bracket 169 and is provided with a square portion 168' adapted to be engaged by a wrench or crank member (not shown) whereby shaft 168 may be manually rotated for actuating the bar 133. The bar 133 is provided with a T-slot 70 133' which, as shown in Figure 13, is arranged with the enlarged portion thereof in the side of the bar facing the roll shaft assemblies 88, and extends from within a short distance of rack 166 to the opposite end thereof. In the enlarged 75 head portion of the slot 133' is mounted a plu-

rality of nuts 170, one for each roll shaft assembly 89. In each nut 170 is screw-threaded one end of a clamping rod 171 which, as shown in Figure 16, extends outwardly through the small or narrow portion of the slot 133' and into the adjacent housing 124 by entering a hole 172 provided in an inwardly extending flange 129' provided at the lower end of each side member 129 (see Figures 12 and 16).

The upper end of the rod 171 passes through 10 a suitable aperture provided in a laterally disposed boss 173 formed on one of the side members 129 a short distance below the upper portion 128 of housing 124 and into a guide opening 174 provided in the housing portion 128.

The clamping rod 171 is provided with a diametrically disposed cam slot 176 arranged adjacent the upper or outer face of the boss 173, the outer end wall 176' of slot 176 being inclined to the axis of the rod to form a cam surface.

In the slot 176 is mounted a cam plate 177 adapted to coat with the boss 173 and cam surface 176' upon movement of the plate transversely of the rod 171 for producing a limited outward longitudinal movement of the rod. A 20 wear plate or washer 178 may, as shown in Figure 16, be positioned on rod 171 between the cam plate 177 and boss 173. The cam plate 177 is moved relative to the rod 171 and boss 173 by means of a rod 179 which is screw-threaded 30 in the outer end of the plate and extends forwardly therefrom through a suitable hole 180 formed in the adjacent guide flanges 143 (see Figures 12 and 16). The outer end of rod 179 is enlarged to provide a shoulder 181 adapted to engage the forward surface of the flange member 143 for limiting the inward longitudinal movement of the rod 179 relative to the housing 124. The outer end of rod 179 is provided with a square socket 179' adapted to receive 40 a wrench or the like (not shown) by which the rod may be manually rotated for producing movement of the cam plate 177. When cam plate 177 is moved outwardly it will effect movement of the rod 171 in a direction away from 45 the positioning bar 133 and the bar 133 will be clamped to the lower ends of side members 129 whereby the roll shaft assembly 89 may be moved, when the fastening bolts 125 therefor are loosened, in unison with the positioning bar 133. 50 When the rod 179 is rotated in a reverse direction to permit the cam plate 177 to move inwardly, the rod 171 will be permitted to move toward the positioning bar 133 and release the clamping action between the bar 133 and housing 124.

As will be readily understood, the roll shaft assemblies 88 connected to plate 14 have but one adjustment, namely, longitudinally of the frame 3, and the means for producing this adjustment when the bolts 96 and 104 are loosened 60 comprises a screw shaft 184, which extends longitudinally through the frame 3 and housings 95 with the ends thereof journaled in one of the side members, as 15, of the frame (see Figure 14). The outer end portion of the shaft 184 is provided with an annular flange 185 which contacts with the side member 15 and a retaining collar 186 secured to the side member 15, as shown in Figure 14, for maintaining the shaft 184 against axial movement relative to the frame 3. The outer end of the shaft 184 is provided with a square portion 184' adapted to be engaged by a wrench or crank member (not shown) whereby the shaft may be manually rotated.

In the lower portion of each housing 95 is positioned a half-nut member 188 which is pivotally connected to the housing 95 by a pin 189 at the rear of the shaft 184, as shown in Figures 14 and 18. Each nut member 188 is provided with a screw-threaded semi-circular recess 190 in the upper edge thereof adapted to engage the screw threads 187 on the shaft 184. The nut member 188 extends a short distance 10 forwardly from the recess 190, and has the forward end thereof provided with a slot 192 extending transversely thereof. In the slot 192 is positioned a pin 193 which is mounted in one end of a sectional shaft 194 in eccentric relation 15 therewith (see Figures 14, 18 and 19). The inner end of shaft 194 is journaled in an intermediate wall 196 formed in the housing 95. The shaft 194 extends through the forward wall of the housing 95, and has the outer end thereof 20 provided with a square portion 194' adapted to receive a wrench or a similar tool by which the shaft may be manually rotated.

It will thus be seen that when the nut 188 is in meshing engagement with the screw threads 187, the particular roll shaft assembly 88 to which the nut is connected may be moved longitudinally of the frame 3 by the rotation of the shaft 184 in a direction depending upon the direction of rotation of said shaft. During this movement of the roll shaft assembly 88, the corresponding gear housing 86 will be moved in unison therewith, and the gear 115 mounted on the drive shaft 69 will move in unison with the housing 86 longitudinally of the shaft 89 in meshing engagement with the gear member 114 for maintaining the straightening roll shaft 100 associated with the roll shaft assembly in continuous operative connection with the drive shaft 69.

In the construction shown, the gear housing 87 for each of the roll shaft assemblies 89 of straightening unit H is adjustably supported by the bottom plate 14 independently of the housing 124. As shown more clearly in Figures 1 and 9, each gear housing 87 for straightening unit H is mounted upon the upper surface of a support 200 which is secured to the bed plate 14 to extend longitudinally of the plate adjacent the rear edge thereof. This support 200 is provided with two inverted T-slots 201, in the upper surface thereof, arranged in uniform spaced relation longitudinally of the support 200. Each gear housing 87 is adjustably secured to the support 200 by bolts 202 mounted in said T-slots 201. Mounted in each housing 87 is a stub shaft 204 upon which is mounted a worm gear 205 which is in meshing engagement with a worm 206 secured to the shaft 10 by a key 207, whereby the worm will be positively rotated by the shaft and at the same time is free to move axially along said shaft during the adjustment of the gear housing 87 relative to the support 200 and shaft 10. The shaft 204 is operatively connected with a respective straightening roll shaft 146 by means of a pair of universal joints 208 and a shaft 209, as shown in Figure 9. The shaft 209 is composed of two sections mounted in telescopic relation with each other to permit 60 the free relative movement of the corresponding roll shaft assembly and gear housing 87. It will be understood that the sections of the shaft 209 are splined to each other, whereby rotation of one section will produce a corresponding rotation of the other section.

While I have shown and described in detail the construction of the two series of roll shaft assemblies 88 and 89 located in the horizontal straightening unit H and means for adjusting such assemblies relative to each other as well as the means for operating the straightening rolls connected therewith, it is to be understood that the two series of roll shaft assemblies of the vertical straightening unit V, the means for adjusting the same relative to each other and the means 10 for operating the straightening rolls connected therewith are constructed and operated in the same manner as those associated with the horizontal unit H. As shown in Figure 6, the roll shaft assemblies 88, in the vertical unit V, and the bearing members 103 associated therewith are each mounted upon the rear plate 6, while the roll shaft assemblies 89 are mounted upon the front plate 5. Likewise, the front plate 5 is provided with a bearing surface 156 along the 15 upper longitudinal edge thereof which is adapted to be engaged by thrust brackets 154 mounted upon the arms 150 associated with each roll shaft assembly 89 for preventing lateral vibratory movement of the straightening roll shafts 146 20 associated therewith.

Furthermore, it will be noted, that the gear housings 86 for the roll shaft assemblies 88 of straightening unit V are connected with the housings 95 of the roll shaft assemblies and adjustably connected with the rear plate 6, while the gear housings 87 are adjustably connected with the support 200 which is secured to the rear plate 6. Also, the shafts 209 for the series 30 of roll shaft assemblies 89 connected with the front plate 5 extend upwardly from the respective gear casings 87 in vertical planes for driving the straightening roll shafts 146. The straightening rolls, as 211 and 212, connected with the roll shaft assemblies 88 and 89 respectively of the 35 vertical unit V, are secured to their respective shafts in the same manner in which the rolls 107 and 147 of the horizontal unit H are connected to their shafts that is, by a thrust collar or bearing 109 and a nut 108.

The straightening rolls 211 and 212 are each provided with two distinct peripheral grooves or passes arranged in spaced relation longitudinally of the rolls to each other. These grooves, as will readily be understood, are formed in their 40 respective rolls to conform to the contour of the particular pieces of work which are to be straightened. That is, in the illustration chosen, the upper positioned grooves, as 211' and 212', are shown as being adapted to engage opposite side 45 surfaces of one class of work, as an I-beam, see Figure 21, while the lower positioned grooves or passes 211'' and 212'' are shown as being adapted to engage opposite vertical sides of a second class of work as a Z-bar. Likewise, the 50 straightening rolls 107 and 147 associated with the horizontal straightening unit H are each provided with two distinct peripheral grooves or passes arranged in spaced relation to each other 55 axially of the rolls.

The rolls 107 are each provided with peripheral grooves 107' and 107'', while the rolls 147 are provided with peripheral grooves 147' and 147''. The grooves 107' and 147' are adapted, as shown 60 in Figure 20, to receive the upper and lower horizontal portions of the I-beam therein, while the grooves 107'' and 147'' are adapted to engage the lower upper horizontal portions respectively of the Z-bar.

It will now be observed that before operating the machine, the vertical and horizontal unit V and H may be adjusted if necessary to bring complementary work receiving grooves or passes

5 of the straightening rolls therein into cooperative alignment with each other for engaging a specific piece of work. For instance, if an I-beam, as I, Figures 20 and 21, is to be straightened, the frame 2 of the vertical unit V may be moved 10 horizontally upon the base 1 by the rotation of screws 48 through the medium of the stub shaft 36', chain 44, shaft 32, worms and worm gears 31 and 39 to bring the vertical plane Z'-Z' extending midway between the axes A'-A', B'-B', 15 of rotation of rolls 211 and 212 respectively into cooperative alignment with vertical medial plane Z-Z passing through the complementary grooves 147' and 147 of the horizontal unit H. Likewise, the frame 3 of the horizontal unit H may be 20 adjusted vertically by the rotation of the screws 27 through the medium of the stub shaft 36, gears 31 and 38, shaft 32 and gears 31 and 30 to bring the horizontal plane X-X extending midway between the axes A-A, B-B of rotation of 25 rolls 167 and 167 respectively into cooperative alignment with the horizontal medial plane X'-X' of the complementary grooves 211' and 212' of the straightening rolls of the unit V.

It will also be understood that before the machine is operated to perform the straightening operation upon a given piece of work, the roll shaft assemblies 88 and 89 of each unit V and H may be adjusted longitudinally of the respective frames 2 and 3 to bring the straightening rolls associated therewith into proper spaced relation, depending upon the size or character of the work, with the coacting rolls of the corresponding unit. This adjustment of the roll shaft assemblies is accomplished by moving one series 40 of rolls at a time; to illustrate: considering first that the roll shaft assemblies 88 are to be adjusted relative to the series of roll shaft assemblies 89 in the vertical unit V—all of the nut members 188, except one, are moved to or maintained 45 in the inoperative position out of engagement with the shaft 184. The bolts 97 and 104 associated with the particular assembly having operative connection with shaft 184 may then be loosened after which the assembly is moved longitudinally of the frame 2 by the operator turning 50 the shaft 184 in one direction or the other, depending upon the direction it is desired to move the roll shaft assembly. After this particular roll shaft assembly has been thus moved longitudinally of the frame 2 to the desired position 55 thereof, the assembly and bearing bracket 103 is secured to the rear plate 6 by tightening the bolts 97 and 104.

The nut member 188 is then moved out of operative engagement with the shaft 184, in the manner hereinbefore described, by manipulation of the respective shaft 194. Another one of the roll shaft assemblies 188 is next released from the rear plate 6 by the loosening of the bolts 97 and 104 associated therewith, after which the nut member 188 connected with this particular roll shaft assembly is brought into operative engagement with the shaft 184 and said shaft is then rotated to move the assembly to the desired position. This second assembly is then secured to the rear plate 6 by tightening the bolts 97 and 105 associated therewith and the nut member 188 is moved out of engagement with the shaft 184. In like manner, the remaining roll shaft

assemblies of this series is adjusted in the frame 2 to bring the same into predetermined spaced relation with the adjacent roll shaft assemblies of the same series.

The roll shaft assemblies 89 of the companion series in the unit V may next be adjusted, one at a time, to bring the same into proper spaced relation with each other and with the roll shaft assemblies 88 of the other series in said unit. In adjusting the roll shaft assemblies 89, a selected one is released from the front plate 5 by loosening the bolts 125 connected therewith. As the bolts 125 are loosened, the roll shaft assembly will be slidably supported by the supporting bars 134 in spaced relation to the roll shaft assemblies 88 adjacent thereto. All of the roll shaft assemblies 89 are to be released from clamping engagement with the positioning bar 133 by inward movement of the cam plates 177 through the medium of the screws 179 or be maintained out of clamping engagement with bar 133, with the exception of the roll shaft assembly which has been loosened from the front plate 5. If the positioning bar 133 is not clamped to the loose assembly it is first clamped to said assembly by means of shaft 179 and cam plate 177 and is then moved longitudinally in the frame 2 by the manipulation of the shaft 168 and pinion 167. As the bar 133 is thus moved longitudinally in one direction or the other, a corresponding movement of the roll shaft assembly 89 connected therewith will be produced to bring the assembly 89 into the desired position relative to the adjacent roll shaft assemblies 88 of the companion series. After the first shaft assembly 89 is thus positioned, the same is released from clamping engagement with the positioning bar 133 by the inward movement of the cam plate 177 connected therewith, and then this roll shaft assembly is secured in position by tightening the bolts 125. In like manner, the remaining roll shaft assemblies 89 of the unit V are moved, one at a time, into proper spaced relation with the adjacent roll shaft assemblies of the companion series and then secured in position.

It will be understood however, that while I have explained a specific method of procedure in adjusting the two series of roll shaft assemblies in the vertical unit V, other methods may be as readily followed, for instance, the roll shaft assemblies of the two series may be adjusted alternately or the series comprising roll shaft assemblies 89 may be all adjusted prior to the adjustment of the roll shaft assemblies 88 of the other series.

In like manner, the roll shaft assemblies 88 and 89 in the horizontal straightening unit H are adjusted, one at a time, to bring the same into the required spaced relation with each other depending upon the size and shape of the work to be straightened. After the roll shaft assemblies 88 and 89 of both units V and H have thus been properly positioned relative to each other longitudinally of the respective frames 2 and 3, the roll shaft assemblies 89 of each unit are next adjusted in a direction toward or from the path of movement of the work through the machine to bring the peripheral surfaces of the straightening rolls associated therewith into such intersecting relation with the general path of movement of the work between the rolls as to effect the desired bending operation of the work. This adjustment of the roll shaft assemblies 89 toward the path of movement of the work is effected by the manipulation of the shaft 160, through the

medium of the gear members 161, 162 and nuts 163.

During the adjustment of the roll shaft assemblies 88, of both straightening units, it will be understood that the gear casings 86 connected therewith will move in unison with the housings 95, while the beveled gears 115, mounted on a drive shaft 69, will move in unison with said casings 86 along the shaft 69 and will, therefore, always remain in meshing engagement with the corresponding beveled gear 114 connected with the roll supporting shaft 100.

If the roll shaft assemblies 89 are moved a considerable distance relative to the supporting frames therefor during the positioning thereof so as to bring the roll supporting shafts 146 thereof considerably out of alignment with the shafts 204 connected therewith, and thus interfere with the smooth operation of the machine, the shafts 204 may be brought into substantially coaxial alignment with the corresponding shafts 146 by adjusting the gear casings 87 longitudinally of the support 200, after the bolts 292 have been loosened. If the lateral adjustment of the roll shaft assemblies 89 is only slight, relative to the shafts 204, it will be obvious that the gear casings 87 may remain in the set position upon the support 200, and any inaccuracy in the alignment of the shaft 204 and 146 with each other will be compensated for through the medium of the universal joints 208 and sectional shaft 209. The machine is now ready to operate for straightening pieces of work as I-beam I adapted to be received in the straightening roll grooves 211' and 212' and 107' and 147'.

When it is desired to straighten pieces of work which are adapted to be operatively received in the straightening roll grooves 211' and 212' and 107' and 147', it will be understood that the machine will be readjusted in the manner above described to bring these latter grooves of the two units into cooperative relation with each other. That is, the vertical unit V will be adjusted horizontally on the base 1 to bring the vertical plane Z-Z' into coincidental relation with the vertical medial plane O-O of the grooves 107' and 147' of the straightening unit H, while the straightening unit H will be adjusted vertically to bring the plane X-X into coincidental relation with the horizontal medial plane Y-Y of the grooves 211' and 212' of the straightening unit V. Also, the roll shaft assemblies 88 and 89 of the two units may be adjusted, if necessary, in the manner above described, to bring the same into proper relation with each other to remove any undulations in the surface of the work.

It will now be understood that straightening rolls, having two or more work receiving grooves or passes arranged in spaced relation to each other axially of the rolls, may be adjusted so that the rolls may be utilized to straighten different pieces of work adapted to be received in said grooves or passes without the necessity of changing the rolls or rearranging them on their respective shafts. When it is necessary to change a straightening roll, this may be readily accomplished by loosening the bolts 104 or 149 for securing the bracket member 103 or 148 in supporting relation with its respective shaft, after which the particular bearing member may be readily removed from its support by drawing the same outwardly and permitting the bolts to pass through the elongated slot 103' or 149' associated therewith, as will be readily understood. After the particular bearing has thus been removed, the

nut 108 is removed from the shaft after which the particular straightening roll may be replaced by another straightening roll of required specifications and said latter roll secured in place by screw-threading the nut 108 back on to the shaft. After the new straightening roll is thus secured to its respective supporting shaft, the bearing member 103 or 148 is again secured in supporting relation with the shaft by fastening the same to the plate 6 or 14 of the unit V 10 or H, or to the arm 150, as the case may be.

It often occurs, when straightening metal bars, that the stresses produced thereon by the straightening rolls in the second straightening unit counteract, to a certain degree, the action on the bar of the first straightening unit, as V, entered by the bar with the result the bar is warped or tends to twist laterally in a direction substantially normal to the stresses produced thereon by the straightening rolls in the second unit. In order to overcome the action of these stresses upon the bar being straightened, I have provided means whereby one of the intermediate straightening rolls of one of the series of the second or horizontal unit H may be adjusted axially to a limited degree. This construction is shown more particularly in Figure 15 and consists in mounting the roll supporting shaft, as 146', in bearings 215 and 216 which are adapted for adjustment axially of the shaft. To explain in detail: the bearing 215, mounted in the forward end of the bearing box 142', has the inner bearing race 217 thereof clamped to the shaft 146' between a collar or annular flange 218 provided on said shaft, and nuts 219 screw-threaded on the shaft so that the inner bearing race 217 will be caused to move axially with the shaft. The rolling members, as 220, of the bearing are mounted in annular grooves provided in the peripheral surface of the inner bearing race 217 to move axially in unison with said latter bearing race and slidably contact with the outer bearing race 221 to move axially relative thereto, said outer bearing 221 to move axially relative thereto, said outer bearing race being secured to the adjacent portion of the bearing box 142, as illustrated, so as to remain in fixed relation therewith.

The bearing member 216, mounted in the inner end of the bearing box 142', has the inner bearing race 222 clamped to the shaft 146' between a shoulder 223 formed on said shaft, and nuts 224 screw-threaded on the shaft adjacent the rear end of the bearing box 142'. The outer bearing race 225 of the bearing 216 is clamped to the interior of a bearing supporting member 226 between a shoulder 227 formed thereon and a nut 228 screw-threaded into the rear end portion of the bearing support 226 so that any axial movement of the bearing support 226 will be transmitted through the members of the bearing 216 to the shaft 146'. The bearing support 226 has the inner end thereof maintained in screw-threaded engagement, as at 229, with the adjacent portion of the bearing box 142' so that the bearing support 226 may be moved axially in either direction relative to the bearing box 142' by the screw-threads 228 upon relative rotation of said bearing support and bearing box. It will thus be seen that in order to bring the 70 grooves or passes of the straightening roll carried by the shaft 146' out of normal cooperating alignment with the remaining straightening rolls of the same straightening unit, it is only necessary to rotate the bearing support 226 in one direc- 75

tion or the other to produce a corresponding axial movement of the shaft 146' and the straightening roll carried thereby. During this axial movement of the shaft 146', the outer end thereof moves axially relative to the bearing member 148 connected with the arm 150.

In order that this axial adjustment of the shaft 146' and the straightening roll carried thereby may be readily accomplished, whether the machine is in operation or not, I have provided the bearing support 226 with gear teeth 231 formed in the peripheral edge of an annular flange 228' formed on the outer end portion of the bearing support 226. A pinion 232, mounted upon the inner end of a shaft 233, is in constant engagement with the gear teeth 231. This shaft 233 is rotatably mounted in bearing members 234 and 235 associated with the arm 150 at one side of the longitudinal center of said arm and has the outer end thereof extended a short distance beyond the outer end of the arm 150 and provided with a square portion 233' adapted to be engaged by a wrench, crank or the like, whereby said shaft and the pinion 232 may be manually rotated.

It will now be observed that inasmuch as the straightening rolls of both series of each straightening unit V and H are power driven in unison, the work will usually be driven through the straightening units without the aid of specially arranged pinch or feeding rolls. However, it will be noted that inasmuch as all of the roll shaft assemblies of each unit are adapted to be adjusted longitudinally of the supporting frame therefor, any straightening roll of one series may be brought into the transverse plane passing through the axis of an adjacent straightening roll of the other series, normal to the path of movement of the work, as illustrated at the right-hand side of the unit V in Figure 1, to form coating pinch or feeding rolls.

Although I have shown and particularly described the preferred embodiment of my invention, I do not wish to be limited to the exact construction shown, as various changes, both in the form and relation of the parts thereof, may readily be made without departing from the spirit of the invention as set forth in the appended claims.

50 I claim:

1. In a metal part straightening machine of the class having two series of straightening rolls arranged to operate in different substantially parallel planes to receive the work to be straightened therebetween, supporting means for said rolls including a frame, a plurality of bearing supporting housings, one housing for each roll, means securing the housings of one series of rolls to one side of the frame, separate means releasably securing the housing of the second series of rolls to the opposite side of the frame, means for adjusting said housings of said second series of rolls relative to each other in directions substantially parallel with said planes of operation of the rolls comprising a bar slidably mounted in said frame for movement in a plane substantially parallel with said first mentioned planes, means for actuating said bar, and means carried by the housings of said second series of rolls for releasably securing each of said housings to said bar independently of the remaining rolls of said latter series.

2. A device as in claim 1 having separate means for adjusting the straightening rolls of one of said series toward and from the

straightening rolls of the other series to increase or decrease the distance between said parallel planes.

3. In a metal part straightening machine of the class having two series of straightening rolls arranged to operate in different substantially parallel planes to receive the work to be straightened between them, supporting means for said rolls including a frame, a plurality of bearing supporting housings, one housing for each roll, means releasably securing the housings of the first of said series of rolls to one side of the frame, separate means releasably securing the housings of the second series of rolls to the opposite side of the frame, means for adjusting the housings of one of said series of rolls relative to the housings of the other series of rolls comprising a positioning bar slidably mounted in said frame intermediate the housings of said two series of rolls for movement in a plane extending substantially parallel with said parallel planes, means for actuating said bar, and means for releasably securing each of the housings of at least one of the series of rolls to said bar.

4. In a metal part straightening machine of the class having two series of straightening rolls arranged to operate in different substantially parallel planes to receive the work to be straightened between them, supporting means for said rolls including a frame, a plurality of bearing supporting housings, one housing for each roll, means releasably securing the housings of the first of said series of rolls to one side of the frame, separate means releasably securing the housings of the second series of rolls to the opposite side of the frame, means for adjusting the housings of one of said series of rolls relative to the housings of the other series of rolls comprising a positioning bar slidably mounted in said frame intermediate the housings of said two series of rolls for movement in a direction substantially parallel with said planes of operation of said rolls, means for actuating said bar, means for releasably securing each of the housings of the second series of rolls to said bar, and separate means for adjusting the housings of the first series of rolls with respect to said housings of said second series of rolls.

5. A straightening machine as in claim 4 wherein the latter adjusting means includes a screw shaft journaled in the frame and extending through the housings of said second series of rolls in spaced relation to said positioning bar, a plurality of nut members for the first series of housings, one for each housing, means connected with each nut member for moving the same into and out of threaded engagement with the shaft, and separate means for rotating said shaft.

6. In a metal part straightening machine of the class having two series of straightening rolls arranged to operate in different substantially parallel planes to receive the work to be straightened between them, supporting means for said rolls including a frame, a plurality of housings, one housing for each roll, means securing the housings of the first series of rolls to one side of the frame, separate means releasably securing the housings of the second series of rolls to the opposite side of the frame in spaced relation to said housings of the first series of rolls, means for adjusting the housings of said second series of rolls relative to the housings of said first series of rolls comprising a positioning bar slidably mounted in said frame intermediate the housings of said two series of rolls, means for

actuating said bar, means for releasably securing each of the housings of said second series of rolls to said bar, and supporting means connected with the frame and extending between the housings 5 of said two series of rolls for slidably supporting the housings of said second series of rolls when the said latter housings are released from the frame.

7. A device as in claim 6 having guide means 10 operatively connected with the frame and with the supporting means for maintaining the housings of the second series of rolls against lateral displacement during the adjustment of the housings.

15 8. In a metal part straightening machine of the class having two series of straightening rolls arranged to operate in different substantially parallel planes to receive the work to be straightened between them, supporting means for said 20 rolls including a frame, a plurality of bearing supporting housings, one housing for each roll, means releasably securing the housings of the first series of rolls to one side of the frame, separate means releasably securing the housings of the 25 second series of rolls to said frame in spaced relation to said housings of said first series of rolls, means for adjusting the housings of said first series of rolls in a direction substantially parallel with said planes of operation of the 30 rolls relative to the frame and to the housings of the second series of rolls, separate means connected with the housings of the second series of rolls for producing adjustment thereof relative to the frame and to said housings of said first 35 series of rolls in a direction substantially parallel with said planes of operation of the rolls, and means including a guide bar mounted intermediate the housings of said two series of rolls having sliding engagement with said housings for 40 maintaining the same against lateral displacement relative to each other during said adjustment thereof.

9. In a metal part straightening machine of the class having two series of straightening rolls 45 arranged to operate in different substantially parallel planes to receive the work to be straightened between them, supporting means for said rolls including a frame, a plurality of housings, one housing for each roll, means releasably securing the housings of the first of said series 50 of rolls to one side of the frame, separate means securing the housings of the second of said series of rolls to the opposite side of the frame in spaced relation to the housings of said first series of rolls, means for adjusting the housings of said first series of rolls relative to the housings of said second series of rolls comprising a screw shaft journaled in the frame, a plurality of nut members, one for each of the housings of said 55 first series of rolls, means connecting each nut member with its respective housing for movement relative thereto, manually operated control means connected with each housing of said first series of rolls and operatively engaging the nut member 60 thereof for bringing said nut member into and out of screw-threaded engagement with the screw shaft, and means for rotating said screw shaft.

10. In a machine for straightening metal parts 70 of the class having two series of straightening rolls, a supporting frame therefor, a plurality of shafts, one for each straightening roll, the rolls of at least one of said series being mounted on their respective shafts intermediate the ends of 75 said shafts, inner and outer bearing means for

each shaft of said latter series of rolls positioned at opposite ends of the roll carried thereby, a plurality of housings carried by said frame, one housing for each of said latter series of shafts, means operatively connecting the inner bearing 5 means of each shaft with a respective one of said housings, means for adjusting the housings of said one of the series of rolls relative to the housings of the other series of rolls, and thrust members associated with the outer bearing 10 means, each of said thrust members being connected with a respective one of said latter housings to move therewith and slidably contacting with the frame for maintaining the outer bearing means against lateral vibration with respect to the axis of the respective shaft. 15

11. A device as in claim 10 having means for adjusting a shaft of one of said series axially with respect to said housing therefor.

12. In a metal part straightening machine, a 20 shaft, a straightening roll mounted on the shaft intermediate the ends thereof, a supporting means, means operably connecting the shaft to said supporting means, including inner bearing members rotatably supporting the shaft at the 25 inner side of the straightening roll, a bearing box for the inner bearing members, means adjustably connecting the bearing box to the supporting means, whereby the shaft and straightening roll may be moved relative to the supporting means 30 into various operative positions, an outer bearing means fixedly connected to the bearing box to move therewith and rotatably supporting the shaft at the outer side of the straightening roll, and a thrust element interposed between the 35 outer bearing means and the supporting means for maintaining that portion of the shaft engaging the outer bearing means against lateral vibration, said thrust element being fixedly connected with one of said latter means and having sliding 40 contact with the other one of said latter means during said adjustment of the shaft relative to the supporting means.

13. In a straightening machine of the class described having two series of straightening rolls 45 arranged to operate in different substantially parallel planes to receive the work to be straightened between them, supporting means for said rolls including a frame, a plurality of bearing supporting housings, one housing for each roll, means securing the housings of one series of rolls to one side of the frame, separate means slidably and releasably securing the housings of the second series of rolls to said frame in opposed relation to the 50 housings of the first series of rolls, means for adjusting said housings of said second series of rolls relative to the housings of the first series of rolls in directions substantially normal to the axis of rotation of the rolls thereof including a screw shaft common to said housings of the second series journaled in said frame, nut members connected with said latter housings movable into and out of operative engagement with said screw shaft, and means connected with said latter housings to move therewith for actuating said nut 55 members independently of each other.

14. In a straightening machine of the class described having two series of straightening rolls arranged to operate in different substantially parallel planes to receive the work to be straightened 70 between them, supporting means for said rolls including a frame, a plurality of bearing supporting housings, one housing for each roll, means adjustably securing the housings of the first series of rolls to the frame, separate means securing the 75

- 5 housings of the second series of rolls to said frame in opposed relation to the housings of the first series of rolls, means for adjusting said housing of said first series of rolls relative to the frame and to the housing of the second series of rolls in directions longitudinally of the frame including a bar common to said housing of said first series movably mounted in said frame, means for actuating said bar, and separate manually operated means connected with each of said latter housings to move therewith having clamping engagement with the bar for releasably securing the housings to said bar independently of each other.
- 10 15. A straightening machine as set forth in claim 14 having guide means positioned longitudinally of the frame in operative engagement with the two series of housings for guiding and supporting the housings of the first series during 20 the adjustment thereof.
- 15 16. In a straightening machine of the class described having two series of straightening rolls arranged to operate in different substantially parallel planes to receive the work to be straightened 25 between them, supporting means for said rolls including a frame, means operatively connecting the straightening rolls of the first series to the frame, separate means securing the straightening rolls of the second series to said frame in co- 30 operative relation with the rolls of the first series comprising a plurality of housing members, one housing for each of said rolls, means operatively connecting the straightening rolls of said second series with said housing members including bearing 35 boxes connected with said housings for movement with respect thereto, means adjustably connecting said housings with the frame whereby said housings may be moved with respect to the frame in directions substantially normal to the 40 movement of the bearing boxes, manually operated means including an actuating member connected with the frame arranged common to said housings and a plurality of connecting means carried by said housings selectively engageable 45 with said actuating member for adjusting the housings, and separate means connected with the housings independently of the frame for adjusting said bearing boxes.
- 45 17. In a metal part straightening machine, having two series of straightening rolls arranged to operate in different substantially parallel planes to receive the work to be straightened between them, supporting means for said rolls including a frame, a plurality of bearing supporting 50 housings, one housing for each roll, means adjustably securing the housings to the frame with the housings of one series of rolls arranged in opposed slightly spaced relation with the housings of the other series of rolls, whereby the 55 housings of both series may be adjusted longitudinally of the frame independently of the housings of the other series and of each other, separate means for adjusting the housings of one series with respect to the housings of the other series including a member connected with the frame and common to the housings of said series, and guide means connected with the frame and extending longitudinally thereof between the two 60 series of housings in sliding engagement with said 65 housings for maintaining the housings of both series against lateral movement with respect to each other during adjustment thereof.
- 70 18. A straightening machine as set forth in claim 17 wherein adjusting members for one of said series of housings are mounted intermediate

the housings of both series and in co-operative engagement with the guide means to be supported by said latter means.

19. In a straightening machine of the class described, a base, two straightening units mounted on said base, each unit comprising two series of straightening rolls and a supporting frame therefor, the rolls of one unit being connected with the corresponding frame to rotate about axes extending at substantially right angles to the axes of rotation of the straightening rolls of the other unit, means for adjusting each of said frames on the base in directions extending substantially normal to the directions of movement of the other frame to bring the rolls of one unit into co-operative alignment with the rolls of the other unit, means for driving the rolls of both units in unison with each other comprising a single drive element mounted on the base at one side of said frames, two pairs of drive shafts, one pair of said drive shafts for each unit, each of said pairs of drive shafts being connected with the corresponding frame to rotate about spaced substantially parallel axes and to move with said frame in fixed relation thereto, means operatively connecting each of said drive shafts with a respective series of straightening rolls, and separate means including extensible shafts operatively connecting each pair of drive shafts with the drive element.

20. In a straightening machine of the class described having a plurality of straightening rolls, supporting means for said rolls including shafts and bearing supporting elements associated with said shafts adjustable in directions substantially normal to the axis of rotation of the rolls whereby said rolls may be adjusted toward or from each other, power means for rotating the rolls in unison, means for producing unitary adjustment of one of the straightening rolls axially independently of the remaining rolls including a control member rotatably carried by the bearing supporting elements associated with said one of the rolls for movement with respect thereto, said control member being normally maintained stationary during the rotation of the rolls and having operative connection with the shaft for the roll and with said supporting element so constructed and arranged that upon movement of the control member relative to the supporting element axial movement of the shaft is produced with respect to said element, and manually operated means connected with said control member and functioning independently of the power operated means for rotating said control member during the operation of the rolls by said power means.

21. In a straightening machine of the class described having a plurality of straightening rolls, supporting means for said rolls including shafts and bearing supporting elements for the shafts adjustable in directions normal to the axis of rotation of the rolls whereby the rolls may be adjusted toward and from each other, power means for rotating the rolls in unison, means for producing unitary adjustment of one of the straightening rolls axially independently of the remaining rolls including a control member positioned at the rear end of said one of the rolls and having screw-threaded engagement with the bearing supporting element for said roll, said control member being operatively connected with the shaft for the roll to produce axial movement of said shaft as said control member is rotated with respect to the bearing carrying element, and manually operated means operatively connected

with the control member and including a member extending to the front end of said straightening roll functioning independently of the power operated means for rotating said control member 5 during the operation of the rolls by the power means.

22. In a straightening machine of the class described, a base, two straightening units mounted on said base, each unit comprising two series of 10 straightening rolls and a supporting frame therefor, the rolls of one unit being connected with the corresponding frame to rotate about axes extending at substantially right angles to the axes of rotation of the straightening rolls of the other 15 unit, means for adjusting each of said frames on the base in directions extending substantially

normal to the directions of movement of the other frame to bring the rolls of one unit into cooperative alignment with the rolls of the other unit, means for driving the rolls of both units in unison with each other comprising a single drive element mounted on the base at one side of said frames, two drive shafts, one for each unit, each of said drive shafts being connected with the corresponding frame to move with said frame in fixed relation thereto, means operatively connecting each of said drive shafts with a respective series of straightening rolls, and separate means including extensible shafts operatively connecting each of said drive shafts with the drive element. 15
